Des. 222,579

Patented Nov. 9, 1971

222,579

CARTON FOR GLASSES

Richard K. Oglesbee, Lancaster, Ohio, assignor to Anchor
Hocking Corporation, Lancaster, Ohio

Filed Sept. 17, 1970, Ser. No. 25,037

Term of patent 14 years

Int. Cl. D9—03

U.S. Cl. D9—176

Fig. 1

Fig. 2

FIG. 2

FIG. 3

FIG. 4

FIG. 1 is a perspective view of a carton for glasses showing my new design;

FIG. 2 is a side elevation thereof, the other side being identical;

FIG. 3 is a top plan view thereof;

FIG. 4 is an end elevation thereof, the other end being identical, and

FIG. 5 is a bottom plan.

I claim:

The ornamental design for a carton for glasses, substantially as shown and described.
